UNITED STATES PATENT OFFICE.

FRANK ADAMAC, OF LAURELTON, NEW YORK, ASSIGNOR TO RUDOLPH FELIX, DOING BUSINESS AS THE OVALITE COMPANY, OF NEW YORK, N. Y.

DESIGN FOR A LIGHTING-FIXTURE BRACKET.

Application filed September 17, 1924. Serial No. 10,804. Term of patent 7 years.

To all whom it may concern:

Be it known that I, FRANK ADAMAC, a citizen of the United States, and a resident of Laurelton, county of Queens, and State of New York, have invented a new, original, and ornamental Design for Lighting-Fixture Brackets, of which the following is a specification, reference being had to the

accompanying drawing, forming a part hereof.

The drawing shows a perspective view of the lighting fixture bracket.

I claim:

The ornamental design for a lighting fixture bracket substantially as shown.

FRANK ADAMAC.
